ALFRED GRIMONT, OF VENICE, AND HERBERT G. KATT, OF LOS ANGELES, CALIFORNIA.

TOOL.

Application filed March 9, 1921. Serial No. 451,073.

To all whom it may concern:

Be it known that we, ALFRED GRIMONT and HERBERT G. KATT, both citizens of the United States, residing in Venice and Los Angeles, respectively, county of Los Angeles, State of California, have jointly invented new and useful Improvements in Tools, of which the following is a specification.

10 This invention relates to a tool and more specifically to a combination tool embodying a wrench and a screwdriver, and it is an object of the invention to provide a simple effective tool of this character for use in connection with machinery and devices of various kinds.

In mechanisms of various kinds there are frequently screws and nuts in recesses and inconvenient places. When there is only a screw, or only a nut, ordinary tools, such as wrenches and screwdrivers, can be used to effect the necessary adjustments or operations. However when there is both a screw and a nut, for instance, when a set-screw or 25 adjusting screw is set by a lock nut, ordinary tools are not effective and it is frequently necessary to remove or detach parts of the machine or device in order to properly actuate both the nut and screw. Such 30 a situation as this occurs in the horn provided on a popular well-known automobile, namely, the Ford automobile. This horn has a diaphragm adapted to be operated by an electro-magnet and a screw is carried in 35 the diaphragm and has a plate on its end to cooperate with the electro-magnet. The screw is adjustable in the diaphragm to regulate the gap between the electro-magnet and the plate and is adapted to be set by a 40 lock-nut. The screw and lock-nut are at the inner or small end part of the horn but cannot be operated from the mouth of the horn by ordinary tools.

An object of this invention is to provide a 45 tool for simultaneously operating a nut and screw, that is, to move the nut and screw at the same time, to move the screw relative to the nut, or to move the nut relative to the screw. The tool can be shaped or proportioned to operate in recesses and inconvenient places where it would be impossible to operate an ordinary wrench and screwdriver. With the tool of the present invention the screw and lock-nut of the horn hereinabove mentioned can be easily and accu-

rately adjusted and set from the mouth of the horn and without removing or detaching any part or parts of the horn, as is necessary when ordinary tools are used.

As we have stated, the horn above referred to is one instance where a nut and screw are arranged in an inconvenient place. It is to be understood that the tool provided by this invention is not in any way limited or restricted to use in connection with a horn, or like device, of the particular character herein set forth, but that it may be used in connection with machines and devices for any uses or purposes. The horn provided on a Ford automobile is a typical and well-known 60 instance where a screw and nut are provided in an ordinary inaccessible place. Throughout this specification we refer to the horn provided on a Ford automobile merely as a typical instance where the tool may be used 65 and to facilitate a clear understanding of the invention.

A particular feature of the invention is the extreme simplicity and cheapness of construction of the device. The invention provides a tool which is simple, effective, and inexpensive, and which is extremely handy and convenient for use.

The various objects and features of the invention will be best and more fully understood from the following detail description of a typical embodiment of the invention, throughout which reference is had to the accompanying drawings, in which—

Figure 1 is a partial sectional view of a 90 horn such as is provided on a Ford automobile showing the tool provided by the present invention in position to operate both the screw and lock-nut of the horn; Fig. 2 is an enlarged detail sectional view of the device provided by the present invention; Fig. 3 is an end elevation of the device, being a view taken as indicated by line 3—3 on Fig. 2; Fig. 4 is an enlarged detail sectional view of the inner end portion of the horn and the tool, showing the tool in position to operate both the set-screw and lock-nut; Fig. 5 is a view similar to a portion of Fig. 4 showing the tool in position to operate only the lock-nut; and Fig. 6 is a view similar to Fig. 5 95 showing the tool in position to operate only the screw.

Throughout the drawings numeral 10 designates an electric horn of the type provided on the Ford automobile. The horn com-

prises, generally, a diaphragm 11, an electro-magnet 12 for operating the diaphragm 11, a casing 13 for the electro-magnet 12 and rear side of the diaphragm 11, a casing 14 for the front side of the diaphragm 11, and a tapered or flaring horn 15 extending from the central portion of the casing 14 in the manner clearly illustrated in the drawings. A boss 16 is secured to the center of the diaphragm 11 and a screw 17 is screw-threaded in the boss 16, extending through the boss and diaphragm and carrying a plate 18 at the inner side of the diaphragm 11 opposite the electro-magnet 12. The end of the screw 17 at the outside of the diaphragm 11 is slotted to receive a screwdriver in order that it may be adjusted to vary the position of the plate 18 relative to the electro-magnet 12. A lock-nut 20 is carried on the outer end portion of the screw 17 to set or lock the screw in its adjusted position. The horn is adapted to be operated by alternating current generated by the power plant of the machine and the screw 17 is adapted to be adjusted and set in position where the plate 18 is the proper distance from the electro-magnet 12 to give the desired tone or noise. The horn is adapted to operate with alternating currents of the frequency generated by the power plant of a Ford automobile and will not satisfactorily operate with ordinary alternating current such as is used for heating, lighting and commercial purposes. For this reason the screw 17, and therefore the plate 18, must be adjusted when the horn is in place on the machine, or it must be adjusted and then placed on the machine for trial. In ordinary practise the horn is removed from the machine, is clamped in a vise, and is connected with a Ford generator. The adjusting is then done with ordinary tools through the horn. When adjusted the horn is replaced in the machine. This method is costly and not altogether satisfactory. Very often when a horn is adjusted to be operated by one generator it will not be properly operated by another generator.

The tool provided by the present invention comprises, generally, a frame 25, a wrench 26, and a screw-driver 27. The wrench 26 is carried at one end of the frame 25, while the screwdriver 27 is carried in the frame 25 to be concentric with the wrench 26. As far as the present invention is concerned the frame 25 may be of any desired size, proportions, or construction and may support or carry the wrench 26 and the screwdriver 27 in any desired manner. In the preferred form of the invention, however, the frame 25 comprises a comparatively long body part 30 provided at its inner end with a cap 31 and at its outer end with a cap 32. In practice it is found desirable to form the body 30 of a section of pipe or tubing and to screw-thread the caps 31 and 32

onto its end. With this construction it is obvious how the frame may be made of any desired length and how it can be easily and inexpensively replaced if broken or damaged.

In accordance with the preferred form of the invention, the outer part 34 of the cap 31 is round, as shown in Fig. 3, and the wrench 26 is arranged concentrically on the cap 31. In the form of the invention shown in the drawings the wrench 26 is a socket wrench and is formed integrally with the cap 31. When this construction is employed it is preferred that the tool be provided with a plurality of caps 31, formed with wrenches of different sizes and shapes. This allows the tool to be used in connection with nuts of various sizes and shapes. It will be readily understood, of course, how the cap 31 can be very easily and quickly removed and replaced due to its being screw-threaded on the end of the body 30.

The screwdriver 27 may be of simple construction, for instance, it may comprise a straight shank 40, the inner end of which is carried in a bore 41 formed concentrically in the cap 31 and opening into the socket 26, and the outer end of which is carried in a bore 42 formed concentrically in the cap 32 and a boss 43 formed on the cap 32. The flat screw-engaging part 45 is formed on the extreme inner end of the shank 40 within the wrench 26, while a handle 47 is formed at the extreme outer end of the shank 40 outside of the cap 32. The screw-engaging part 45 may be shaped in proportion to properly cooperate with the slot in the outer end of the screw 17, while the handle 27 may be of any desired shape, being preferably shaped so that it can be easily and conveniently gripped by the operator of the tool. A pin 50 may be carried in the shank 40 within the body 30 to engage the cap 32 and limit the outward movement of the screwdriver in the manner clearly shown in Fig. 2. The inward movement of the screwdriver will be limited by the handle 47 engaging the cap 32. The pin 50 is preferably detachable from the shank 40 so that the screwdriver can be removed from the other parts of the tool when the cap 32 is detached from the body 30. In practice the screwdriver may be advantageously formed from a single bar or rod by simply forming the flat screw-engaging part 45 at one end and the handle 47 at the other.

The particular tool illustrated in the drawings is designed particularly to be used in operating the screw and nut of the horn 10. When it is desired to adjust the screw 17 the tool provided by the invention is arranged in the horn 15 in the manner clearly illustrated in Figs. 1 and 4. The round portion 34 of the cap 31 engages the horn 15, centering the wrench 26 so that it accurately

engages or fits over the nut 20. If the wrench 26 does not fit over the nut 20 when the tool is moved longitudinally into the horn it is merely necessary to rotate the tool, 5 that is, the frame of the tool, to bring the wrench in proper register with the nut 20, it being held in proper line with the nut 20 by the cooperation of the round part 34 of the cap 31 and the horn 15. When the 10 wrench is in place on the nut 20 the screwdriver, being carried concentrically with the wrench 26, is in position to be moved into engagement with the screw 17. By turning the screwdriver to the proper position the 15 flat screw-engaging portion 45 will enter the slot of the screw so that the screw can be turned. With the tool thus in place, that is, with the wrench on the nut and the screwdriver in engagement with the screw, 20 it is possible for the operator to simultaneously move both the screw and nut, to hold the screw and move the nut, or to hold the nut and move the screw. The wrench and screwdriver can be very easily and conveniently 25 moved independently of each other, thus making it possible to operate the nut and screw independently of each other. When adjusting the horn 10 the screw is first held while the nut 20 is loosened, where- 30 upon the screw is adjusted until the plate 18 is properly spaced from the electro-magnet, whereupon the screw is again held and the nut 20 is set or tightened. It will be obvious how the tool may be very easily 35 and conveniently placed in the horn so that the nut is engaged by the wrench and the screw by the screwdriver, and how the proper adjusting operations may be very easily, quickly, and accurately effected in a 40 very convenient manner. It has been found in practice that it is not necessary to provide a handle on the frame 25 when the tool is to be used in connection with horns and the like. However, if the tool is to be used in 45 connection with heavy machinery it may be found desirable to form the frame with a suitable handle in order that the wrench can be effectively operated.

In Fig. 5 we show the tool in position 50 where the wrench is in position to operate the nut but where the screwdriver is not in engagement with the screw 17. In Fig. 6 the tool is shown with the screwdriver in engagement with the screw 17, while the 55 wrench is not in engagement with the nut 20. These two figures of the drawings illustrate how the tool may be used to operate either the nut or a screw whether or not they are in combination with each other 60 as hereinabove described.

Having described only a typical embodiment of our invention, we do not wish to limit or restrict ourselves to the particular details hereinabove set forth but wish to 65 reserve to ourselves any changes or modi-

fications that may appear to those skilled in the art or that may fall within the scope of the following claims.

Having described a preferred form of our invention, we claim:

1. A tool of the character described embodying in combination, a body, a cap at one end of the body, a socket wrench on said cap, a cap at the other end of the body, and a screwdriver carried by said caps to extend 70 concentrically into the wrench.

2. A tool of the character described, embodying in combination, a body, a detachable cap at one end of the body, a socket wrench on said cap, a cap at the other end 80 of the body, and a screwdriver carried by said caps to extend concentrically into the wrench.

3. A tool of the character described, embodying in combination, a body, a cap at 85 one end of the body, a socket wrench formed integrally on said cap, a cap at the other end of the body, and a screwdriver carried by said caps to extend concentrically into the wrench.

4. A tool of the character described, embodying in combination, a cylindrical body, a cap screw-threaded on each end of the body, a socket wrench formed concentrically on one of said caps, a screwdriver 95 loosely carried by the caps to extend concentrically into the wrench, and means to prevent displacement of the screwdriver from the cap.

5. A tool for use in connection with a 100 horn having a screw and a nut in its small end, including two independently operable parts, one a socket wrench and the other a screw-driver arranged in the socket wrench, and means adapted to cooperate with the 105 horn to guide the parts into engagement with the nut and screw.

6. A tool of the character described embodying in combination, a body, a socket wrench carried by the body, and a screwdriver carried by the body concentrically with the socket-wrench and so that it is freely longitudinally and rotatably movable independently of the socket-wrench.

7. A tool of the character described embodying in combination, a body, a socket wrench provided on one end of the body, and a screw-driver carried by the body so that its operating end extends into the socket wrench and so that it is freely longitudinally 115 and rotatably operable independently of the socket wrench.

8. A tool of the character described embodying in combination, a body, a socket wrench on one end of the body so that the 125 body forms an operating handle for it, a screw-driver carried by the body so that its operating end is concentric with and is at the socket wrench and so that its handle end extends from the other end of the body, 130

the screw-driver being freely longitudinally and rotatably movable relative to the socket wrench.

9. A tool for use in connection with a horn which is circular in cross-sectional configuration and which has a screw and a nut at its small end, comprising a socket wrench, a screw-driver rotatably and longitudinally movable relative to the socket wrench, and a circular part in connection

with the wrench and screw-driver and adapted to fit in the horn to guide the wrench and screw-driver.

In witness that we claim the foregoing we have hereunto subscribed our names this 1st 15 day of March, 1921.

ALFRED GRIMONT.
HERBERT G. KATT.
